UNITED STATES PATENT OFFICE.

EDWARD M. PIKE AND JOSEPH B. SCHOPP, OF CHENOA, ILLINOIS.

TILE AND POTTERY KILN.

SPECIFICATION forming part of Letters Patent No. 340,003, dated April 13, 1886.

Application filed October 26, 1885. Serial No. 180,912. (No model.)

To all whom it may concern:

Be it known that we, EDWARD M. PIKE and JOSEPH B. SCHOPP, citizens of the United States, residing at Chenoa, in the county of McLean and State of Illinois, have invented 5 certain new and useful Improvements in Pottery-Kilns, of which the following is a specification, reference being had therein to the accompanying drawings.

10 This invention relates to certain improvements in kilns for burning earthenware; and it has for its objects to provide a kiln which will be economical in the consumption of fuel and in which the articles may be more thoroughly and uniformly burned than heretofore. 15 These objects we obtain by the means illustrated in the accompanying drawings, in which—

Figure 1 represents a central vertical sectional view of the improved kiln, taken on the line $x x$ of Fig. 2; and Fig. 2 a horizontal sectional view of the furnace. Fig. 3 represents a perspective view of a portion of the furnace, showing the door-frame and the means of securing the encircling bands to the same. 25

The letter A indicates a kiln, which is constructed of brick-work or any other suitable material. The lower portion or substructure of the kiln, indicated by the letter a, is greater 30 in diameter than the upper portion, and in the walls of the said substructure are formed the fire-chambers B, which have vertical flues C, extending upward and terminating in the upper part of the kiln. The kiln is cylindrical in form, and is provided with a dome-shaped crown, D, as shown in Fig. 1 of the drawings. The substructure or lower part of the kiln is constructed with a circular or annular flue, E, which extends entirely around 35 it, and with cross flues F, connecting with said circular flue. These flues connect with a transverse diametrical flue, G, which leads outward to a smoke-stack, H.

The letter I indicates the floor of the kiln, which is constructed of fire-brick, and which 45 is located between the substructure and superstructure of the same. The said floor is built of fire-bricks so laid as to leave interstices K, by means of which communication is established between the upper and lower portions 50 of the kiln. The door of the kiln is provided with an arched iron frame, L, to which is attached, at proper intervals and by suitable means, a series of metallic bands, M, which extend around the kiln and bind the 55 walls securely together. It will be seen that as thus constructed the kiln is a downdraft kiln, and that the flames and products of combustion distribute themselves thoroughly around the articles, thus insuring the most 60 uniform and perfect baking of the same.

Having thus described our invention, what we claim, and desire to secure by Letters Patent, is—

1. The combination, with the superstructure, 65 of the furnace having a series of furnaces, B, connecting with the upper part thereof, and the intervening floor having flues I, the substructure being provided with an annular flue, E, cross-flues F, and transverse flue G, 70 the latter leading to the smoke-stack, substantially as and for the purposes specified.

2. The combination, with the door of the furnace, of the iron frame L, located therein, and the bands extending around the furnace, 75 the ends of said bands at the door being bent and fastened over the outer edge of the frame, substantially as specified.

In testimony whereof we affix our signatures in presence of two witnesses.

EDWARD M. PIKE.
JOSEPH B. SCHOPP.
